Primary Examiner — Elizabeth J Oswecki(74) *Attorney, Agent, or Firm* — Kilpatrick Townsend & Stockton LLP(57) **CLAIM**

The ornamental design for a flexible printed circuit board, as shown and described.

DESCRIPTION

FIG. 1 is a perspective view of a flexible printed circuit board showing my design, in a flat state;

FIG. 2 is a front view thereof;

FIG. 3 is a left side view thereof;

FIG. 4 is a rear view thereof;

FIG. 5 is another perspective view thereof, in a folded state;

FIG. 6 is a front view thereof;

FIG. 7 is a left side view thereof; and,

FIG. 8 is a rear view thereof.

The broken lines shown in the drawings represent portions of the flexible printed circuit board, that form no part of the claimed design.
